United States Patent Office.

F. B. MORSE, OF NEW HAVEN, CONNECTICUT

Letters Patent No. 65,761, dated June 11, 1867; antedated May 21, 1867.

IMPROVEMENT IN JOINT FOR CARRIAGE-BRACES.

The Schedule referred to in these Letters Patent and making part of the same.

TO ALL WHOM IT MAY CONCERN:

Be it known that I, F. B. MORSE, of New Haven, in the county of New Haven, and State of Connecticut, have invented a new Improvement in Joint for Carriage-Braces; and I do hereby declare the following, when taken in connection with the accompanying drawings and the letters of reference marked theron, to be a full, clear, and exact description of the same, and which said drawings constitute part of this specification, and represent, in—

Figure 1, a side view.

Figure 2, an under edge view.

Figure 3, a longitudinal section through the centre of the joint; and in

Figures 4 and 5, edge views of the two parts detached.

This invention relates particularly to an improvement in the joint used for supporting carriage-tops, and known to the trade as "stump joint;" yet the novel construction of this joint, renders it applicable to other places and uses, and the invention consists in an internal cone-seat, combined with an external cone, which forms what may be termed a dove-tail hinge-joint.

In order to the clear understanding of my invention, I will proceed to describe the same, as illustrated in the accompanying drawings.

A is the one part, B the other part, formed so as to be welded to the braces, or so as to be attached to whatever is to be applied to the joint or hinge. The one part A has an ear, C, formed upon one end, equal to about one-half the thickness of the piece A, and conical, diminishing from the centre outward. Upon the upper surface of the conical ear C is formed a reverse cone, D, as seen in fig. 4, so as to leave a shoulder, a, entirely around the cone D, and forming a corresponding conical recess, d, between the cone D and the part A, all as seen in fig. 4. The other part B has a corresponding ear, E, formed as seen in fig. 5. In its centre a cavity is formed corresponding to the cone D on the other part, and its outer surface, so as to fill and fit in the recess d, as seen in fig. 3. The recess d should be a little narrower at the base than at the top, and the cone D may, if preferred, extend through the ear E. The end of the part B, at f, is formed to receive and fit closely the ear C, as seen in figs. 3 and 5. The two parts thus formed are set together as seen in figs. 1, 2, and 3, and when so set the internal cone, combined with the external conical surfaces, forms a strong and perfect joint, relieving the pivot from all strain, save that of simply holding the two parts together, the entire wear occasioned by the movement or operation of the joint being upon the conical surfaces, resisting to the fullest extent all tendency to rattle or strain.

I do not broadly claim a joint having upon one ear a cone and the other a corresponding recess, as such was patented to me April 23, 1867; but what I do claim as new and useful, and desire to secure by Letters Patent, is—

The cone D, formed upon an inverted conical ear, C, on the one part, combined with a corresponding ear, E, provided with an internal conical seat upon the other part, to correspond to the cone D, the whole constructed substantially as herein set forth.

F. B. MORSE.
